175,427

TRAY OR SIMILAR ARTICLE

Oscar W. Martha, Wallingford, Conn., assignor to R. Wallace & Sons Manufacturing Company, Wallingford, Conn., a corporation of Connecticut

Application April 4, 1955, Serial No. 35,342

Term of patent 14 years

(Cl. D44—10)

FIG. 1

FIG. 2

FIG. 3

Fig. 1 is a top plan view of a tray showing my new design in which the portion shown in dotted lines corresponds to the portion shown in full lines;

Fig. 2 is a cross-sectional view taken on lines 2—2 of Fig. 1;

Fig. 3 is a cross-sectional view taken on lines 3—3 of Fig. 1; and

Fig. 4 is a cross-sectional view taken on lines 4—4 of Fig. 1.

I claim:

The ornamental design for a tray or similar article, substantially as shown.
